CLAIM

We claim the ornamental design for a vehicle door plate with switch mount, as shown and described.

DESCRIPTION

FIG. 1 is a perspective view of the vehicle door plate with switch mount;

FIG. 2 is a left view thereof;

FIG. 3 is a front view thereof;

FIG. 4 is a right view thereof;

FIG. 5 is a rear view thereof;

FIG. 6 is a top view thereof; and

FIG. 7 is a bottom view thereof.

In the drawings, the broken lines show portions of a vehicle door plate with switch mount and form no part of the claimed design.
